LIQUID DEPTH RECORDING INSTRUMENT

Joseph Alan Huntsman, Broomall, Pa., assignor to
Pro-Tech, Inc., Springfield, Pa., a corporation of
Pennsylvania

Filed June 24, 1964, Ser. No. 80,553

Term of patent 14 years

(Cl. D52—6)

Fig. 1.

Fig. 2.

FIG. 1 is a front elevational view of a liquid depth recording instrument, showing my new design.

FIG. 2 is a perspective view thereof shown on a reduced scale.

The undisclosed side of the instrument is substantially the same as the side shown, except for the presence of the three elements, and the rear and bottom are flat and plain in appearance.

The essential features of the design reside in the portions shown in full lines.

I claim:

The ornamental design for a liquid depth recording instrument, as shown and described.
